SHOWER RING

Orloff W. Holden, Chicago, Ill., assignor to Knickerbocker Rubber Company, Chicago, Ill., a corporation of Illinois

Application March 16, 1938, Serial No. 196,122

9 Claims. (Cl. 4—157)

This invention has to do with portable shower rings of the type adapted to be placed around the neck of the user with the bottom of the ring resting on the shoulders.

When the ordinary portable shower ring is used and no curtaining facilities are available—which is not infrequently the case—considerable splashing of the floors and walls is likely to occur.

The object of this invention is to provide an improved ring which will keep the water from splashing off away from the body of the user, will allow a free unobstructed flow of the water from the perforations at all points about the ring, and will tend to remain in a flat condition without sagging when being handled and used while yielding readily from a circular to an oval shape under lateral pressure.

While the foregoing statements are indicative in a general way of the nature of the invention, other more specific objects and advantages will be apparent to those skilled in the art upon a full understanding of the construction of the improved ring.

A preferred embodiment of the invention is presented herein for the purpose of exemplification, but it will of course be appreciated that the invention is susceptible of embodiment in other structurally modified forms coming equally within the scope of the appended claims.

30 In the accompanying drawing:

Fig. 1 is a top plan view of a shower ring constructed in accordance with the invention;

Fig. 2 is a vertical diametric section through the ring, taken on the line 2—2 of Fig. 1;

Fig. 3 is a fragmentary side view of a portion of the ring at the location of the hose connection, viewed from the line 3—3 of Fig. 1;

Fig. 4 is a fragmentary side view of the ring at the location of the detachable connection between the two semi-circular sections, showing the sections detached; and

Fig. 5 is an enlarged section through one side of the ring.

The portable shower ring shown in the drawing is made of rubber tubing, in two semi-circular sections 10 and 11. The ring is of such size as to slip easily over the head of the user and rest upon the shoulders. The sections 10 and 11 are connected at one side of the ring to a T-shaped metal fitting 12, which fitting is adapted to be connected to a water faucet by means of a long rubber hose 13. The sections are coupled together at the opposite side of the ring by means of resiliently interfitting snap buttons 14

and 15 which are attached to wooden members 16 plugged into the ends of the sections.

The tubing is of octagonal cross-section, as shown in Fig. 5, although it may be of any other desired cross-section, and is provided with a large number of small jet-discharging perforations 17, which perforations are all preferably located in the same plane and are directed inwardly and downwardly at an angle of about 45°. The tubing is provided at its bottom with an integrally formed downwardly extending flange-like rib 18. This rib is located outwardly of the perforations, with its lower edge well below the level of the perforations. The inner and outer sides of the rib 18 are preferably provided with minute corrugations 19 which extend circumferentially of the ring. While the rib 18 is preferably located in line with the center of the tubing it could of course be located toward the outside of the tubing with measurably good results.

The rib 18 serves several purposes. It forms an anti-splash shield which prevents the jets of water from the perforations 17 splashing away from the body after striking it. It keeps the perforated portion of the tubing from having to support the ring, thus allowing a free unobstructed flow of the water from the perforations at all points about the ring. It affords considerable rigidity to the ring in such a manner as to keep the latter from sagging from its initially flat condition, while at the same time permitting the ring to yield readily from a circular to an oval shape upon lateral pressure. The corrugations on the ring help to keep the latter from slipping from any position in which placed

30 on the shoulders.

35 The snap buttons 14 and 15 permit the two semi-circular sections 10 and 11 of the ring to be easily separated or coupled together, with the result that after the water has been turned on and adjusted to the right temperature the ring can be easily placed about the neck without having to be slipped over the head, thereby allowing the hair to be kept dry and also permitting instant removal of the ring should an unexpected increase in the temperature of the water make removal necessary.

I claim:

1. A tubular shower ring provided with a large number of jet-discharging perforations, and a flange-like rib located at the bottom of the ring outwardly of the perforations with the lower edge of the rib well below the level of the perforations.

2. A tubular rubber shower ring provided with

- 5 a large number of inwardly and downwardly directed jet-discharging perforations, and an integrally formed flange-like rib located at the center of the bottom of the ring outwardly of the perforations with the lower edge of the rib well below the level of the perforations.
- 10 3. A tubular rubber shower ring provided with a large number of inwardly and downwardly directed jet-discharging perforations, and an integrally formed flange-like rib located at the center of the bottom of the ring outwardly of the perforations with the lower edge of the rib well below the level of the perforations, said rib being provided on its inner and outer surfaces with circumferentially extending corrugations.
- 15 4. A tubular rubber shower ring provided with a large number of inwardly and downwardly directed jet-discharging perforations, and an integrally formed flange-like rib located at the center of the bottom of the ring outwardly of the perforations with the lower edge of the rib well below the level of the perforations, said ring being composed of two semi-circular sections which are detachably coupled together at one side of the ring.
- 20 5. In a device of the class described, a tubular ring having a water inlet and a series of jet discharge openings about a wall thereof, said ring also having a fending rib extending downwardly exterior to and surrounding the jet openings, the ring adapted to embrace the neck with the rib resting upon the shoulders of the bather.
- 25 6. In a device of the class described, a tubular ring having a water inlet and a series of closely adjacent jet discharge openings about the wall thereof directed downwardly, said ring also having an integral rib extending downwardly exterior to and surrounding the jet openings, the ring adapted to embrace the neck with the rib resting upon the shoulders of the bather.
- 30 7. In a device of the class described, a tubular rubber ring having a water inlet at one side and a series of minute jet discharge openings about a wall thereof directed inwardly and downwardly, said ring also having an integral cylindrical rib extending downwardly exterior to and surrounding the jet openings, the ring adapted to embrace the neck with the rib resting upon the shoulders of the bather.
- 35 8. In a device of the class described, a tubular rubber ring having a water inlet at one side and a series of closely adjacent minute jet discharge openings about a wall thereof and directed inwardly and downwardly, said ring also having an integral cylindrical fending rib extending downwardly exterior to and surrounding the jet openings and forming a downward projection of the ring, the ring adapted to embrace the neck with the rib resting upon the shoulders of the bather.
- 40 9. In a device of the class described, a tubular rubber ring having a water inlet at one side and a series of closely adjacent minute jet discharge openings about the inner and lower wall thereof, said jets inwardly and downwardly directed, said ring also having an integral cylindrical fending rib extending downwardly exterior to and surrounding the jet openings and forming a downward projection of the exterior wall of the ring, the ring adapted to embrace the neck with the rib resting upon the shoulders of the bather.

25 30 35 40 45 ORLOFF W. HOLDEN.
